JAMES DOBSON, OF PHILADELPHIA, PENNSYLVANIA.

MECHANISM FOR PRODUCING UPON THE SURFACE OF PILE FABRICS AN IMITATION
OF THE IRREGULAR CURLY APPEARANCE OF ASTRAKHAN FUR AND THE LIKE.

1,102,484.

Specification of Letters Patent. Patented July 7, 1914.

Application filed January 17, 1914. Serial No. 812,826.

To all whom it may concern:

Be it known that I, JAMES DOBSON, a citizen of the United States, residing in the city of Philadelphia, State of Pennsylvania, have 5 invented certain new and useful improvements in mechanism for producing upon the surface of pile fabrics an imitation of the irregular curly appearance of Astrakhan fur and the like, of which the following is a full, 10 clear, and exact description, reference being had to the accompanying drawings, forming a part of this specification.

My invention relates to mechanism herein-after described, having for its object the production on the pile surface of pile fabrics substantially permanent indentations or im- 15 pressions in imitation of the fur of genuine Astrakhan and Persian lamb skins.

To this end my invented apparatus con- 20 sists of the elements and the combinations of them as hereinafter set forth.

In the accompanying drawings: Figure 1, is a plan view of a machine embodying my invention. Fig. 2, is a side elevation thereof. Fig. 3, is a vertical section thereof, on line 25 3—3 of Fig. 1. Fig. 4, is a plan view of one of the figuring devices. Fig. 5, is a side view of the figuring device shown in Fig. 4. Fig. 6, is a view of a group of figuring devices 30 of different sizes. Fig. 7, is a detail of one of the bearings for the perforated roller shaft. Fig. 8, is a section, on line 8—8 of Fig. 2, showing one of the friction devices. Fig. 9, is a view, partly in elevation and 35 partly broken away, of the perforated roller and its shaft removed from the machine. Fig. 10, is a view, in section, of the perforated roller with the steam pipe applied thereto. Fig. 11, is a view of the finished 40 product of the machine.

Referring to the drawings, the frame of the machine comprises two spaced parallel side standards 2 connected by horizontal tie bars 3 extending therebetween and secured 45 thereto.

Extending between the standards 2 and journaled in suitable bearings therein is a 50 shaft 4 to which is secured a roller 5 carrying a rolled strip of porous fabric 6, such as duck. The fabric 6 extends from the roll 5 to and around idler rollers 7 and thence to a roller 8 upon which it is wound or rolled. The idlers 7 are carried by shafts which are mounted to turn in bearings in the standards

2, and the roller 8 is carried by a shaft 9 which is journaled in bearings 10 on the standards 2. One end of the shaft 9 extends outwardly and has keyed thereon a worm wheel 11, in mesh with a worm 12, secured on a driving shaft 13 which turns in bearings 14 on one of the standards 2. The driving shaft 13 is provided with fast and loose pulleys 15 and 16, respectively, adapted to receive a belt from a source of power to rotate the shaft 13. By shifting the belt from one to the other of the fast and loose pulleys, the shaft 13 may be started and stopped, as desired. When the shaft 13 is rotated, the worm 12 and worm-wheel 11 turn the shaft 9 and roller 8 in the direction of the arrow, 70 and thereby cause the roller 8 to draw the fabric 6 from the roller 5 around the idlers 7 and wind or roll it upon the roller 8.

In order that the fabric 6 may be wound upon the roller 8, under tension, I provide 75 the outwardly-extending end of the roller shaft 4 with a pair of friction disks 17 and 18. The disk 17 is keyed to the shaft 4 and the disk 18 is rotatably mounted on the shaft 4 between the disk 17 and a head or collar 19 80 screwed on to the end of the shaft 4, a yielding washer 20 being interposed between the head 19 and the hub of the disk 18. By adjusting the head 19, the pressure of the disk 18 against the disk 17 may be nicely regu- 85 lated. The disk 18 is provided with ratchet teeth which are engaged by a pawl 21 pivoted on the adjacent standard 2. From this construction it will be seen that when the fabric 6 is drawn from the roller 5, the pawl 21 will prevent the rotation of the disk 18 90 and that the friction between the engaged faces of the disks 17 and 18 will cause the fabric 6 to be drawn from the roller 5 under tension and to be tightly wound upon the 95 roller 8.

The pile fabric 22 to be treated is first wound upon a roller 23 carried by a shaft 24 which is mounted to turn in bearings in the standards 2. From the roller 23, the pile fabric passes over the top of the fabric 6 with its pile surface uppermost between the rollers 7 and 8 and is drawn into the layers of the fabric 6 upon the roller 8, enter- 100 ing between the top of the fabric 6 leading to the roller 8 and the last preceding layer of the fabric 6 rolled upon the roller 8, so that, as the roller 8 rotates, the pile

fabric 22 will be drawn from the roller 23 and rolled upon the roller 8, each layer of pile fabric being inclosed between two layers of the fabric 6. I provide one end of the roller shaft 24 with a friction device 25, which is constructed the same as the friction device, hereinbefore described, for the shaft of the roller 4 so that the pile fabric 22 may also be drawn from the roller 23 under tension.

To further assist in tightly winding the fabric upon the roller 8, I provide a board 26 extending parallel to the roller 8 and carried by end brackets 27 which are pivoted to a rod 28 extending between the standards 2. The board 26 is movable about the axis of the rod 28 toward and from the roller 8 and is pressed against the fabric being rolled thereon by a weight 29 at each end of the board 26. Each weight 29 is attached to one end of a cord or chain 30 which passes over a grooved pulley 31 journaled on a pin on the adjacent standard 2, the other end of the cord 30 being attached to a downwardly-extending arm 32 of the bracket 27 carrying the adjacent end of the board 26.

When the pile fabric 22 passes over the rollers 7 and the upper face of the fabric 6 on its way to the roller 8, the upper or pile surface of the pile fabric receives a quantity of figuring or patterning elements or devices 33 which are placed or scattered promiscuously thereon by hand, in accordance with the generally irregular impressions to be made in the pile in imitation of the fur of the genuine skins. Each figuring device 33 is formed of non-oxidizable and non-corrosible metal, such as aluminum, bent into sinuous form with all the sinuous curves thereof being parallel to a single plane, as clearly shown in Figs. 4 and 5, so that the devices will lie flat upon each other and upon the pile surface of the fabric 45 when dropped or scattered thereon by hand, as shown in Fig. 1. As the fabric is wound upon the roller 8 the figuring devices 33 are carried into and between the pile surface of the pile fabric 22 and the next adjacent 50 layer of the fabric 6, and are thereby caused to embed themselves in the pile of the pile fabric.

The figuring devices 33 are made of different lengths, some having more sinuous curves than others, as shown in Fig. 6, and the devices 33 may also be made of wire of different gages for a greater variety of effects in the finished product.

The roller 8 is made hollow to receive steam, and it is also perforated, as clearly shown in Fig. 9, to permit the steam introduced to the roller 8 to pass through the fabric rolled thereon, for a purpose herein-after explained. The upper portions of 65 the bearings 10 for the shaft 9 are hinged

at 35 and are movable to the dotted line position, shown in Fig. 6, to permit the removal of the shaft 9 and roller 8 from the machine. The upper portions of the bearings 10 are held in the full line position by pivoted bolts 36 and thumb screws 37 thereon engaging the bearings. When the shaft 9 and the roller 8 are removed from the machine, the shaft 9 is withdrawn endwise from the roller and a steam pipe 40 is inserted into the roller 8 as shown in Fig. 9. When the shaft 9 is in the roller 8, a square portion 39 of the shaft fitted to a square opening in the end of the roller causes the roller to turn with the shaft. One end of 75 the pipe 40 has an elbow 41 thereon, between which and the end of the roller 8 a head 42 is provided which surrounds the pipe 40. A packing ring 43 is interposed between the elbow 41 and head 42 and a 80 packing ring 44 is interposed between the head 42 and the adjacent end of the roller 8 to form steam tight joints. The other end of the pipe 40 is closed and is exteriorly 85 screw-threaded for the reception of a head or nut 45 between which and the adjacent end of the roller 8 a packing ring 46 is placed. When the head or nut 45 is removed from the pipe 40 it may be readily inserted into or removed from the roller 8. 90 When the pipe 40 is inserted and the head 45 is applied and tightened, the parts will be drawn tightly against the packing rings 43, 44 and 46, so that no steam will escape from the ends of the roller. The portion of 95 the pipe 40 exposed to the interior of the roller 8 is provided throughout its length with perforations for the even distribution of steam entering the roller. Steam may be readily supplied to the pipe 40 from a 100 suitable source by connecting a pipe leading therefrom to the elbow 41.

The operation is as follows: The shaft 9 and perforated roller 8 are placed upon the machine, the porous fabric 6 is wound upon the roller 5 and drawn therefrom around the rollers 7 and wound several turns around the perforated roller 8. The pile fabric 22 to be treated is wound upon the roller 23 and drawn therefrom to and over the rollers 7 and thence over the top of the fabric 6 and its free end inserted between the upper face of the fabric 6 leading to the roller 8 and the bottom of the outside layer of the fabric 6 around the roller 8, so that the subsequent 115 operation of the machine will wind both fabrics 6 and 22 upon the roller 8 as previously explained. A quantity of the figuring devices 33 are now placed or scattered upon the pile surface of the pile fabric by 120 hand, as shown in Fig. 1, in accordance with the general character of the particular fur to be imitated. Power is now applied to the shaft 13 and both fabrics 6 and 22 are 125 tightly wound upon the roller 8, carrying 130

the figuring devices 33 into the roll of fabric between the pile surface of the pile fabric 22 and the fabric 6 facing the pile surface around the rollers 8. The tight winding of the fabric upon the roller 8 forces the figuring devices 33 into and embeds them in the pile of the pile fabric, and, as the figuring devices are non-compressible and of substantially permanent configuration, they form distinct and well defined indentations or impressions in the pile of the pile fabric. As rapidly as the pile fabric 22 is taken up by the roller 8, the figuring devices 33 are placed or scattered on the pile surface thereof as it passes to the roller 8; and after all the pile fabric has passed to the roller 8, several additional layers of the fabric 6 are wound around the roll of fabric. The shaft 9 and roller 8 are now carrying the roll of fabric removed from the machine, and the shaft 9 is removed from the roller 8 and the pipe 40 applied thereto. The pipe 40 is then connected to a source of dry steam supply and the steam turned on. The dry steam enters the roller 8 and passes therefrom through the perforations therein and through the porous fabric 6 and pile fabric 22 wound upon the roller, the pile fabric being also porous. The steaming operation is continued for about fifteen minutes when the steam is turned off. The roll of fabric is then permitted to remain on the roller 8 until the fabric has thoroughly cooled, thereby setting the pile with the indentations formed therein by the figuring devices 33 and forming substantially permanent impressions in true imitation of the fur of the genuine skins. After cooling, the fabric is unrolled from the roller 8 and the roller 8, shaft 9, figuring devices 33 and porous fabric 6 are returned to the machine for a succeeding operation on a fresh roll of pile fabric.

The figuring devices 33, when placed or scattered upon the pile surface of the pile fabric and lying either singly or crossing each other thereon, provide patterns of the exact form of the impressions or indentations desired to be made in the pile of the pile fabric in true imitation of the curly fur of the genuine skins.

Before the pile fabric is placed upon the roller 23 to be treated as just described, it is treated in the usual manner to cause the pile threads of certain spots or regions to extend in one direction and the pile threads of certain other spots or regions to extend in other directions, in imitation of the pe-

culiar appearance of the fur of the natural skins.

Having thus described my invention, I claim:—

1. Mechanism for producing upon the surface of plain pile fabrics an imitation of the surface appearance of Astrakhan fur and the like, comprising in combination a supporting frame, a hollow and peripherally perforated take-up and compressing roller, means for rotating said roller, means to supply a strip of pile fabric and means to supply a strip of porous fabric both adapted to be delivered to said perforated roller under tension, a series of non-compressible figuring devices of sinuous form adapted to lie flat by gravity upon the surface of the pile fabric and be pressed into the same through said porous fabric, through the action of the take-up hollow roller, and means to introduce steam to said hollow roller.

2. Mechanism of the character recited comprising in combination a supporting frame, a hollow and peripherally perforated roller, means to support it removably on the frame, means to rotate said roller, means to introduce steam to its interior thereof, means to supply a strip of pile fabric and means to supply a strip of porous fabric, to said hollow roller, under tension, and a series of non-compressible and non-oxidizable figuring devices of sinuous form, each having its sinuous curves all substantially parallel to the same plane and adapted, when loosely scattered on the pile fabric as delivered, to assume by gravity a flat position thereon.

3. Mechanism of the character recited comprising in combination a frame, means to support and let off a strip of fabric to be treated, means to support and let off a strip of porous fabric, a hollow and peripherally perforated take-up roller, means to rotate it to draw said pile fabric and porous fabric in alternating relation in each convolution of the roll and in compressed relation, and a series of non-compressible figuring devices of sinuous form adapted to lie flat by gravity and adapted to be compressed in that position between each convolution of the roll.

In testimony whereof, I have hereunto affixed my signature this thirty first day of December, A. D. 1913.

JAMES DOBSON.
